MEDICINE DROPPER

Alex Rothman, Bronx, N. Y.

Application February 27, 1947, Serial No. 731,171

4 Claims. (Cl. 128—233)

1

This invention relates to new and useful improvements in a medicine dropper.

This application is a substitute of my application filed on February 5, 1944, Serial Number 521,169, now abandoned.

More specifically, the invention proposes the construction of a medicine dropper having a resilient bulb for drawing and forcing liquid in and out and which is provided with a small resilient auxiliary bulb extension arranged in a manner to permit a measured quantity of medicine or other liquid to be delivered from the bulb when the small resilient auxiliary bulb is compressed.

A further object of the invention proposes forming the bulbs as an integral unit to permit a big bulb to be pressed for filling the dropper, after which the small bulb may be used to deliver the measured quantity of liquid.

Still another object of the invention proposes the provision of a tubular glass extension mounted upon the large resilient bulb for conveying the liquid to and from the bulbs.

Still another object of the invention proposes the provision of a means upon the auxiliary bulb extension which may be used for limiting the amount of liquid which will be delivered by the dropper each time the auxiliary bulb extension is compressed.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure—

Fig. 1 is a perspective view of a medicine dropper constructed in accordance with this invention.

Fig. 2 is an enlarged vertical sectional view taken on the line 2—2 of Fig. 1.

Fig. 3 is a perspective view of a medicine dropper constructed in accordance with a modification of this invention.

Fig. 4 is an enlarged partial vertical sectional view taken on the line 4—4 of Fig. 3.

Fig. 5 is a vertical sectional view taken on the line 5—5 of Fig. 4.

The medicine dropper, according to this invention, includes a resilient bulb 10. This resilient bulb 10 is formed of rubber or other similar material and is provided with an opening having a beaded edge 11 which is disposed in a complementary recess 12 formed in one end of a tubular

2

glass member 13. The tubular glass member 13 is provided for conveying a liquid to and from the interior of the resilient bulb 10.

At a point disposed opposite the tubular glass member 13 the bulb 10 is provided with a small resilient auxiliary bulb extension 14 which may be used for dispensing one drop at a time, liquid contained within the large bulb 10. This bulb extension 14 is also formed of rubber or other similar material and is integrally formed with the large bulb 10.

The manner of using the medicine dropper, in accordance with this form of the invention, is as follows:

15 The end of the tubular glass member 13 is inserted into a vessel containing the desired medicine or liquid and the large bulb 10 is manually compressed to draw a portion of the liquid into the large bulb 10 through the tubular glass member 13. The small bulb extension 14 is designed to expel one measured drop at each pressure. One advantage of this dropper is that any prescribed number of drops may be administered without the use of electric light. If it is desired 20 to force three drops of the liquid contained within the large bulb 10 from the dropper it is merely necessary to compress the bulb extension 14 three times to force the air therefrom and cause three drops of liquid contained within the bulb 10 to be displaced and discharge through the tubular glass member 13. The three drop example is merely for the purpose of illustration, and the bulb extension 14 might be of design to have any desired capacity.

25 In the modification of the invention shown in Figs. 4 and 5 the resilient auxiliary bulb extension 14' is provided with a means for limiting the amount the auxiliary bulb extension may be compressed to control the quantity of liquid which will be displaced therefrom. In this form 30 of the invention a collar 15 is fixedly mounted within the bulb extension 14' and slidably supports a second tubular collar 16. The end of the tubular collar 16 is provided with a spider 17. A shaft 18 extends from the spider 17 and slidably 35 passes through an extension 19 formed on the auxiliary bulb 14'. The outer end of the shaft 18 is provided with a knob 20 which may be pulled outwards to draw on the shaft 18 and move the tubular collar 16 into an extended position with 40 relation to the collar 15.

45 Normally, the tubular collar 16 will be in a retracted position shown in Fig. 4, permitting the extension 14' to be easily compressed to displace 50 the liquid capacity thereof. However, when the

tubular collar 16 is in its extended position it will act to limit the degree to which the bulb 14' may be compressed and thus limit the amount of liquid it will dispense when compressed. In other respects this form of the invention is similar to that previously shown and like reference numerals identify like parts in each of the several views.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. A medicine dropper comprising a resilient bulb for drawing and forcing liquid in and out, a small resilient auxiliary bulb extension on said bulb for dispensing a small quantity of said liquid, a collar fixedly mounted within said small extension, a second collar slidably extended into said collar, and means for extending said second collar from said first collar to limit the amount the bulb extension may be compressed to control the amount of liquid which will be displaced thereby.

2. A medicine dropper comprising a resilient bulb for drawing and forcing liquid in and out, a small resilient auxiliary bulb extension on said bulb for dispensing a small quantity of said liquid, a collar fixedly mounted within said small extension, a second collar slidably extended into said collar, and means for extending said second collar from said first collar to limit the amount the bulb extension may be compressed to control the amount of liquid which will be displaced thereby.

thereby, comprising a spider mounted across the outer end of said second collar, a shaft extending from said spider and slidably extended through an opposed wall of said bulb extension to be manually pulled out and pushed in to extend and retract said second collar.

3. A medicine dropper comprising a resilient bulb for drawing and forcing liquid in and out, a small resilient auxiliary bulb extension on said bulb for dispensing a small quantity of said liquid, a collar fixedly mounted within said small extension, a second collar slidably extended into said collar, and means for extending said second collar from said first collar to limit the amount the bulb extension may be compressed to control the amount of liquid which will be displaced thereby, comprising a spider mounted across the outer end of said second collar, a shaft extending from said spider and slidably extended through an opposed wall of said bulb extension to be manually pulled out and pushed in to extend and retract said second collar.

20 4. A medicine dropper comprising a resilient bulb for drawing and forcing liquid in and out, a small resilient auxiliary bulb extension on said bulb for dispensing a small quantity of said liquid, a collar fixedly mounted within said small extension, a second collar slidably extended into said collar, and means for extending said second collar from said first collar to limit the amount the bulb extension may be compressed to control the amount of liquid which will be displaced thereby, and means for limiting complete disengagement of said collars.

ALEX ROTHMAN.
